US00D595700S

(12) **United States Design Patent**
Cook et al.

(10) **Patent No.:** US D595,700 S
(45) **Date of Patent:** ** Jul. 7, 2009

(54) **MONOPOLE STRUCTURE**

(75) Inventors: **Bradley J. Cook**, Boulder, CO (US);
Dan J. Welch, Boulder, CO (US)

(73) Assignee: **Structural Components, LLC**, Boulder,
CO (US)

(**) Term: **14 Years**

(21) Appl. No.: **29/326,758**

(22) Filed: **Oct. 23, 2008**

(51) LOC (9) Cl. **14-03**

(52) U.S. Cl. **D14/234**; D14/238

(58) **Field of Classification Search** D14/230–238,
D14/299; 343/700 R, 840, 841, 908; 455/3.02,
455/FOR. 215, 575.2; 52/651.01; D12/115

See application file for complete search history.

(57) **CLAIM**

The ornamental design for monopole structure, as shown and described.

DESCRIPTION

FIG. 1 is a front perspective view;

FIG. 2 is a back perspective view;

FIG. 3 is a front view;

FIG. 4 is a back view;

FIG. 5 is a side view;

FIG. 6 is an opposite side view;

FIG. 7 is a bottom view; and,

FIG. 8 is a top view.

The design is shown broken away in the middle to indicate that a specific length of monopole structure forms no part of the claimed design.
